[57] CLAIM

We claim the ornamental design for an automobile, as shown and described.

DESCRIPTION

FIG. 1 is a right, front, perspective view of the automobile showing our new design;

FIG. 2 a right, rear, perspective view of the automobile showing our new design;

FIG. 3 is a right-side, elevational view of the automobile of FIG. 1, the left-side being essentially a mirror image thereof;

FIG. 4 is a front, elevational view of the automobile of FIG. 1;

FIG. 5 is a rear, elevational view of the automobile of FIG. 1; and,

FIG. 6 is a top plan view of the automobile of FIG. 1. The bottom of the automobile is unornamented.
